UNITED STATES PATENT OFFICE.

PLINY CATUCCI, OF NEWARK, NEW JERSEY, ASSIGNEE, BY MESNE ASSIGNMENTS, TO
OTTO HEINEMAN PHONOGRAPH SUPPLY CO., INC., OF NEW YORK, N. Y., A CORPO-
RATION OF NEW YORK.

ADJUSTABLE PIVOT-BEARING.

1,280,342.

Specification of Letters Patent.

Patented Oct. 1, 1918.

Application filed April 26, 1917. Serial No. 134,596.

To all whom it may concern:

Be it known that I, PLINY CATUCCI, a citizen of the United States, residing in the city of Newark, county of Essex, and State of New Jersey, have invented new and useful Improvements in Adjustable Pivot-Bearings, as set forth in the following specification.

In the best of the modern spring motors used for driving phonographs and talking machines it has become the practice to utilize what has been known as the spiral drive for the governor shaft; that is to say, the governor shaft itself has cut upon it a double thread worm of comparatively quick pitch which engages a worm wheel of corresponding pitch. The worm wheel is mounted upon the turn table driving mandrel with the governor shaft axis in the plane perpendicular to the axis of the driving mandrel, so that the governor shaft is driven from the mandrel through the worm gear.

The adjustment of this worm and worm gear is a very delicate matter. In order to secure a quiet running motor, the engagement of the worm and worm wheel must be very accurately adjusted; otherwise there will be a peculiar whir or buzzing sound, not only disagreeable to the ear, but often destroying the effect of the reproduction. Several methods have been proposed to accomplish this adjustment, so that the teeth of the worm wheel will engage the worm to the proper depth and no more. Among these is the eccentric adjustment, in which the pivot bearings are eccentrically located in a cylindrical bushing, the angular adjustment of which will bring the governor shaft into nearer or more remote engagement with the worm wheel as desired. The difficulty with this means of adjustment lies in the fact that it does not always provide the exact adjustment necessary. It does not preserve the accurate parallelism between the worm threads and the teeth of the worm wheel. The reason for this is that with the eccentric, a complete cycle of adjustment would cause the axis of the governor shaft to generate a cone. The accurate adjustment of the worm and worm wheel can be accomplished only by causing the worm and worm wheel to approach each other in the

plane which shall pass through the axis of the governor shaft and to be perpendicular to the axis of the worm wheel.

55

It is to provide an adjustment of the character just described that I have devised the improvement described in the following specification and illustrated in the accompanying drawings, wherein—

60

Figure 1, is a side elevation of so much of the well known spring motor as may be necessary to gain a full knowledge of my invention.

Fig. 2, is a horizontal section on line 2—2 of Fig. 1.

Fig. 3, is a front elevation of the governor slot bearing and its support.

Similar reference numerals refer to like parts throughout the specification and drawings.

The motor frame 1, is of a well known type and is provided with the bracket stanchions 2, 3 and 4, which serve as bearing supports for the several parts of the motor. In the present case the bridge plate 5, connects the stanchion 2, to the stanchion 4, for the purpose of affording a support for the pivot bearing 6, of the lower end of the mandrel 7, the upper end of said mandrel being located in a bearing in the upper part of the frame 1. The mandrel 7, carries a worm wheel 8, for engagement with the worm 9, upon the governor shaft 10, which is supported by its pivots 11, and 12, in the bearings mounted in the stanchions 2 and 3. The governor is of the usual type used in spring motors and consists of the fixed collar 13, and the sliding collar 14, upon the shaft 10. These collars are connected by the springs 15 and 16, which carry the centrifugal governor weights 17, the action of which is well known. As above described it is necessary that the worm 9, shall accurately mesh with the worm wheel 8. If for any reason there is any inaccuracy of this engagement, a noisy governor will result. One end of the governor shaft may be provided with a fixed bearing as 18, which consists of a cup shaped element inserted in the hole 19, in the stanchion 3, and held in place by means of the set screw 20. In order to secure the best results in the way of durability and accuracy in running I make

95

100

the bearing 18, in the following manner. The inner end is provided with a cavity 21, in which is inserted a hardened steel disk 22. Upon this steel disk is the apertured phosphor bronze bearing 23, which is accurately drilled to receive the pivot 12, on the end of the governor shaft. Both pivot bearings 11 and 12, have their extreme ends hardened and ground spherical. The bearing 18, thus becomes by means of the set screw 20, an adjustable end thrust bearing.

The governor slide bearing is constructed in the following manner:

In the face of the stanchion 2, a groove 24, is milled. Extending from the bottom of this groove 24, to the rear of a stanchion 2, is an elongated slot 25. In the groove 24, is fitted very accurately, the governor slide bearing 26, which consists of a rectangular block of metal with a screw threaded aperture 27, to receive a screw 28, which passes through the slot 25, and by which the block 26, is firmly held in any adjusted position within the groove 24. In the end of the block 26, there is an aperture 29, in which is fitted a small steel disk 30, which serves as an end thrust for the pivot 11. The sleeve bearing 31, is a duplicate of the bearing 23, at the opposite end of the governor shaft, being made of phosphor bronze. The block 26, is provided with a small ball handle 32, by which it may be pushed or pulled along the groove 24, when the set screw 28, is slightly slackened off.

The adjustment of the motor is accomplished by the operator in the following manner:

The motor is set running with the worm 9, in engagement with the worm wheel 8. The operator then slightly slackens up the set screw 28, and then with his ear close to the running motor adjusts the block 26, back and forth in the slot 24, until the adjustment is such that the worm gear is absolutely silent. The operator depends entirely upon his acute sense of hearing to accomplish accurate adjustment. When the point is reached at which no sound is given out by the worm gear, the operator then turns the set screw 28, up tight. He then adjusts the bearing 18, by slackening set screw 20, and pushing in or pulling out said bearing until there is only a very minute end play for the shaft. He then resets the screw 20, and the adjustment is complete.

It will thus be seen that the adjustment of the worm 9, is toward and away from the worm wheel 8, in a straight line, and with the worm and wheel accurately cut as they usually are, there will be no binding of parts either in the bearings, or between worm and wheel. When no audible sound comes from these parts the operator may know that his adjustment is correct.

By my improvement, I am able to make

a great saving in cost of construction over previous forms of governor shaft adjustments, and what is more advantageous a very great saving in time occupied in assembling and adjusting. The purchasing public is more critical now than formerly, and the manufacturer is required to give much attention to accuracy of detail, and the present improvement is but another step in that direction.

I claim:

1. In an adjustable pivot bearing, the combination with a support, there being a groove in said support, of a pivot bearing slide adjustably secured in said groove.

2. In an adjustable pivot bearing, the combination with a support, there being a straight groove in said support, said groove having an elongated slot in the bottom thereof, said slot extending through said support, of a pivot bearing slide movable within said groove, and a screw passing through said slot and into said bearing slide, for securing same in adjusted position within said groove.

3. In an adjustment for spring motor governors, the combination of a governor shaft having a worm thereon, a worm wheel for engaging said worm to drive said shaft and means for adjusting said worm toward and away from said wheel, comprising a pivot bearing slide in which one end of said shaft is pivoted, a support for said slide and an adjusting screw for securing said slide in adjusted position upon said support.

4. In an adjustment for spring motor governors, the combination of a governor shaft having a pivot at each end thereof, an adjustable end thrust pivot bearing for one of said pivots, and a laterally adjustable bearing for the other pivot, each of said bearings being provided with a socket therein, a hard metal disk in each socket, and a metal bushing bearing secured in each socket by forcing the same therein against said disk.

5. In an adjustment for spring motor governors, the combination of a governor shaft having a pivot at each end thereof, a worm on the shaft, a worm wheel for engaging said worm to drive said shaft, means for adjusting said worm toward and away from said wheel, comprising a pivot bearing slide in which one end of said shaft is pivoted, a support for said slide, an adjusting screw for securing said slide in adjusted position upon said support, an adjustable end thrust pivot bearing for one of said pivots, a socket in said bearing, a metal disk in said socket, and a metal bushing bearing secured in said socket.

6. In an adjustment for spring motor governors, the combination of a governor shaft having a pivot at each end thereof, an adjustable end thrust pivot bearing for one of said pivots, a laterally adjustable bear-

ing for the other pivot, each of said bearings being provided with a socket therein, and adjustable screws for securing the bearings in adjusted position.

5 7. In an adjustment for spring motor governors, the combination of a governor shaft having a pivot at each end thereof, an adjustable end thrust pivot bearing for one end of said pivots, a laterally adjustable bearing 10 for the other pivot, each of said bearings being provided with a socket therein, a metal disk in one of said sockets, and a metal bushing bearing secured in one of said sockets by forcing the same therein 15 against said disk.

8: In an adjustment for spring motor governors, the combination of a governor shaft having a pivot at each end thereof, a worm on the shaft, a worm wheel for engaging 20 said worm to drive said shaft, means for adjusting said worm toward and away from said wheel, comprising a pivot bearing slide in which one end of said shaft is pivoted, a support for said slide, an adjustable end 25 thrust pivot bearing for one of said pivots, a socket in said bearing, a metal disk in said socket, a metal bushing bearing secured in said socket, and adjustable screws for securing the bearings in adjusted position.

30 9. In an adjustment for spring motor governors, the combination of a governor

shaft having a pivot at each end thereof, a worm on the shaft, a worm wheel for engaging said worm to drive said shaft, means for adjusting said worm toward and away 35 from said wheel, comprising a pivot bearing slide in which one end of said shaft is pivoted, a support for said slide, an adjustable end thrust pivot bearing for one of said pivots, and adjusting screws for securing 40 said slide and end thrust bearing in adjusted positions upon their respective supports.

10. In an adjustment for spring motor governors, the combination of a governor 45 shaft having a pivot at each end thereof, an adjustable end thrust pivot bearing for one of said pivots, a laterally adjustable bearing for the other pivot, and adjustable screws for securing the bearings in adjusted 50 position.

11. In an adjustment for spring motor governors, the combination of a governor shaft having a pivot at each end thereof, an adjustable end thrust pivot bearing for one 55 end of said pivots, a laterally adjustable bearing for the other pivot, each of said bearings being provided with a socket therein, a metal bushing bearing in one of said sockets, and adjustable screws for securing 60 the bearings in adjusted position.

PLINY CATUCCI.
